CLAIM

The ornamental design for a puzzle board as shown and described.

DESCRIPTION

FIG. 1 is a perspective view of a puzzle board showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the puzzle board where the puzzle board is in a first configuration of use;

FIG. 10 is a perspective view of the puzzle board where the puzzle board is in a second configuration of use;

FIG. 11 is a perspective view of the puzzle board where the puzzle board is in a third configuration of use;

FIG. 12 is a front elevational view thereof; and,

FIG. 13 is an enlarged view of portion 13 shown in FIG. 1. The dash-dash broken lines in the drawings depict portions of the puzzle board that form no part of the claimed design. The dot-dash broken lines in FIGS. 1 and 13 represent boundaries of the enlarged portion and form no part of the claimed design.
